MAGNETICALLY OPERATED PUMP

Filed Sept. 15, 1947

UNITED STATES PATENT OFFICE

2,578,902

MAGNETICALLY OPERATED PUMP

Dale Smith, Englewood, Ohio

Application September 15, 1947, Serial No. 774,025

5 Claims. (Cl. 103—53)

1

This invention relates to a magnetically operated pump.

One object of the invention is to provide a double action magnetically operated pump of a simple compact construction.

A further object of the invention is to provide a double action pump in which the piston is positively moved in both directions by separate magnets.

A further object of the invention is to provide such a pump in which the pumping elements and the magnets are assembled in a unitary structure.

A further object of the invention is to provide such a pump in which the magnets are carried by the pump structure and are enclosed in sealed casings.

A further object of the invention is to provide such a pump in which the magnets are automatically and rapidly energized and deenergized.

A further object of the invention is to provide such a pump with a remote timing mechanism for automatically energizing and deenergizing the magnets.

A further object of the invention is to provide such a pump which may be operated in either a vertical position or a horizontal position, and which may be used for pumping fluids of many kinds.

Other objects of the invention will appear as the pump is described in detail.

In the accompanying drawings Fig. 1 is a longitudinal section taken centrally through a pump embodying the invention; Fig. 2 is a longitudinal section, partly broken away, taken on the line 2—2 of Fig. 1, omitting the piston and piston rod; Fig. 3 is a transverse section taken on the line 3—3 of Fig. 1; and Fig. 4 is a diagram of the magnet circuits and the controlling device therefore.

In these drawings I have illustrated one embodiment of my invention and have shown the same as comprising a supporting structure having therein a cylinder in which operates a piston provided with a piston rod. The structure is also provided with inlet and outlet passages communicating with the cylinder on both sides of the piston. Arranged in line with the cylinder, and preferably supported on the supporting structure, are two magnets each having an armature movable lengthwise of the cylinder and connected with the piston rod. Thus the alternate energization of the two magnets will impart reciprocatory movement to the piston.

In the particular embodiment here illustrated

2

the supporting structure comprises a one piece body 5 having therein a longitudinal bore 6 which constitutes the pump cylinder. The body is also provided with an inlet passage 7 extending lengthwise of the cylinder and here shown as closed at one end and is provided at its other end with an opening 8 to receive the end of a supply pipe 9. The passage 7 is connected with the cylinder, adjacent the respective ends of the latter, by ports 10 in which are arranged inlet valves 11 of a known type. The inlet passage is also provided with openings 12 which are normally closed by plugs 13 but with which a supply pipe or pipes may be connected, and the opening 8 plugged. There is also formed in the body an outlet passage 14 which is here shown closed at one end and as having at its other end an opening 15 to receive the end of a discharge pipe 16 leading to a storage receptacle 17 and having therein an outwardly opening check valve 18. The discharge or outlet opening 14 is connected with the cylinder, adjacent the respective ends of the latter, by ports 19 in which are mounted outlet valves of a known type. The outlet passage is also provided with normally plugged openings 21 with which a discharge pipe or pipes may be connected if desired. Mounted in the cylinder is a piston 22 with which may be connected a piston rod or rods. In the present instance a single piston rod 23 extends through the piston and is rigidly secured thereto, the end portions of the rod extending from the piston to points adjacent the respective ends of the cylinder.

Arranged adjacent to and preferably supported by the supporting structure or body 5 are two electromagnets 24 and 25. In the present arrangement the magnets are in the nature of solenoids and are arranged at the respective ends of the cylinder and are supported directly on the body 5. Each magnet comprises a tubular element 26 having at its inner end a radial flange 27 by which it may be secured to the adjacent end of the body, and preferably having its outer end closed. Mounted on this tubular element is a magnetizing winding 28, and the winding and tubular element are enclosed by an outer shell or casing 29 having at its inner end a radial flange 30 by which it may be secured to the body. As here shown, the flanges of the inner and outer elements are secured to the body by the same screws, 31, suitable gaskets 32 and 33 being interposed between the flange 27 of the inner element 26 and the end of the body and between the flange 27 and the flange 30 of the outer shell,

thus tightly sealing the casing. Each solenoid includes an armature or core 34 supported in the tubular element 26 for longitudinal movement therein, the two armatures being rigidly connected with respective ends of the piston rod 23. The outer shell or casing of one of the solenoids, in the present instance the solenoid 24, is provided with an opening in which is mounted a conduit 35 for conductors 36 which extend through the conduit into the casing 29 and a part of which are connected with the magnetizing winding of the solenoid 24 and another part 37 of which extends through the casing 28 and through a longitudinal opening 38 in the body 5 to the winding of the solenoid 25. Thus the alternate energization of the two solenoids will cause the piston to reciprocate in the cylinder.

Any suitable means may be provided for automatically energizing and deenergizing the two solenoids. As shown in the diagram of Fig. 4 the main circuit, comprising conductors 39 and 40, is adapted to be connected with any suitable power line. One of these conductors, in the present instance 40, is connected by branch circuits 41 and 42 with the solenoids 25 and 24 respectively and these solenoids are connected by conductors 43 and 44 with the respective terminals 45 and 46 of a two way switch 47. The movable member 48 of the switch is adapted for movement into contact with either of the terminals 45 and 46 and is connected by a conductor 49 with the conductor 39 in the main circuit. The movable member 48 of the switch may be moved from one terminal to the other in any suitable manner, as by a finger 50 connected with the movable switch member. The finger 50 is preferably actuated by a continuously rotating timing device 51 which is rotated by a suitable electrically operated device, here shown diagrammatically as an electric clock 52 which is connected with the conductors 39 and 40 of the main circuit. The timing device is provided with means for engaging the finger 50 of the switch and moving the removable member 48 thereof first in one direction and then in the other direction. The main circuit is, of course, provided with a master switch 66 by which the operation of the pump mechanism may be initiated and interrupted. Thus it will be apparent that when the master switch is closed the timing device will operate the two way switch to alternately close the circuits through the magnets and thereby actuate the piston to draw fluid into and to discharge the same from the cylinder. This operation will continue until the master switch is opened or the circuit otherwise broken.

It is also desirable that the circuit should be provided with an automatic pressure controlled cutout to interrupt the operation of the pump when the pressure in the tank 17, or other part of the line, reaches a predetermined limit. As here shown there is interposed in the conductor 39 of the main circuit a switch 55 which is normally urged into engagement with a fixed contact member 56 by a spring 57. A pressure controlled element, such as a bellows 58, is so connected with the tank as by a conduit 59 that it will expand as the pressure rises. Connected with the bellows is a finger 59 which is arranged to engage the switch member 55 and move the same out of engagement with the contact member 56 when the bellows has expanded to a predetermined extent.

It will be apparent from the foregoing description that I have provided a double action, mag-

netically operated pump which is of a simple compact arrangement, is positively operated in both directions, is automatically controlled, can be operated either in a horizontal position or in a vertical position for the pumping of fluids of various kinds, and is well adapted for use both in deep wells and in shallow wells.

While I have shown and described one embodiment of my invention I wish it to be understood that I do not desire to be limited to the details thereof as various modifications may occur to a person skilled in the art.

Having now fully described my invention what I claim as new and desire to secure by Letters Patent is:

1. A magnetically operated pump comprising a body having therein a cylindrical bore constituting a pump cylinder, said body also having therein inlet and discharge passages extending lengthwise of said cylinder for the major portion of the length of the latter, and valve controlled ports connecting each passage with said cylinder adjacent the respective ends of the latter, a piston in said cylinder, solenoids secured to the respective ends of said body and each including a longitudinally movable armature rigidly connected with the adjacent side of said piston in spaced relation thereto, and means for energizing said solenoids automatically to impart reciprocatory movement to said piston.

2. A magnetically operated pump comprising a body having therein a cylindrical bore constituting a pump cylinder, said body also having therein inlet and discharge passages extending lengthwise of said cylinder for the major portion of the length of the latter, and valve controlled ports connecting each passage with said cylinder adjacent the respective ends of the latter, a piston in said cylinder, solenoids secured to the respective ends of said body and each including a longitudinally movable armature rigidly connected with the adjacent side of said piston in spaced relation thereto, said body having therein a third passage which extends for the full length thereof and through which conductors may extend from one end of said body to the solenoid at the other end thereof, and means for energizing said solenoids alternately to impart reciprocatory movement to said piston.

3. A magnetically operated pump comprising a body having therein a cylindrical bore constituting a pump cylinder, said body also having therein inlet and discharge passages extending lengthwise of said cylinder for the major portion of the length of the latter, and valve controlled ports connecting each passage with said cylinder adjacent the respective ends of the latter, a piston in said cylinder, solenoids secured to the respective ends of said body and each including a longitudinally movable armature rigidly connected with the adjacent side of said piston in spaced relation thereto, said body having therein a third passage which extends for the full length thereof, casings enclosing the windings of the respective solenoids, a plurality of conductors extending into one of said casings, a part of said conductors being connected with the winding in said casing and another part of said conductors extending from said casing through said third passage and being connected with the windings in the other of said casings, and means for alternately energizing said solenoids.

4. A magnetically operated pump comprising a body having therein a cylinder, a piston in said cylinder, said body also having therein longitu-

dinal inlet and discharge passages extending for the major portion of the length of said cylinder, valve controlled ports connecting said passages with said cylinder on each side of said piston, solenoids supported by the respective ends of said structure, each solenoid including a tubular element separate from and rigidly secured to said body, a magnetizing winding on said tubular element and an armature supported in said tubular element for movement lengthwise thereof and connected with the adjacent side of said piston, and means for alternately energizing said windings to impart reciprocatory movement to said piston.

5. A magnetically operated pump comprising a part having therein a cylinder, a piston in said cylinder, inlet and discharge conduits communicating with said cylinder in each side of said piston, valves to control the flow of fluid to and from said cylinder, a tubular element supported in line with said cylinder at each end of said body, said tubular element being separate from said body, having rigid sealed connection with the adjacent end thereof and having its outer end closed, a magnetizing winding on each tubular element, a second tubular element extending about and enclosing said winding, said second tubular element having its outer end closed and having its inner end rigidly secured to the adjacent end of said body, armatures supported in

said inner tubular elements for movement lengthwise thereof and rigidly connected with said piston, one of said second tubular elements having an opening through which electrical conductors may enter the same and said body having an opening extending lengthwise thereof through which a part of said conductors may extend from said one of said second tubular elements to the winding in the other of said second tubular elements, and means for alternately energizing said windings to impart reciprocatory movement to said pistons.
